UNITED STATES PATENT OFFICE

CHARLES C. HANSEN, OF CHICAGO, ILLINOIS, ASSIGNOR TO REFRIGERATING SPECIALTIES CO., OF CHICAGO, ILLINOIS, A CORPORATION OF ILLINOIS

CONTROLLING DEVICE FOR REFRIGERATING SYSTEMS

Application filed February 14, 1927. Serial No. 167,981.

The invention relates to controlling devices for refrigerating systems.

In freezing ice-cream by direct expansion systems, it has been found that by using differential temperatures during the freezing of the cream, the product is greater in volume and possesses less density which in many instances is preferred.

The primary object of the invention is to provide an improved controlling device for these freezing systems whereby the operator may quickly and readily set the system to operate at different temperatures or pressures, during the freezing of each batch of ice cream or other freezing operations. This object is attained primarily by providing an automatic valve in the suction line of the refrigerating system between the freezer and the compressor in conjunction with the usual expansion valve which controls the flow of refrigerant to the freezer. This valve is provided with a device whereby it may be set to automatically open at one predetermined pressure, for example fifteen pounds during the first period of the freezing operation, and then set to remain closed until the pressure in the freezer reaches, for example fifty pounds, so that the refrigeration will be finished by the higher temperature refrigerant at the high pressure.

Another object of the invention is to provide a unitary device which is adapted to be included in the suction line and which provides for the quick adjustment for producing the predetermined differential pressures desired.

The invention consists in the several novel features hereinafter set forth and more particularly defined by claims at the conclusion hereof.

In the drawings: Fig. 1 is a diagrammatic view of a refrigerating system embodying the invention. Fig. 2 is a vertical section of the automatic valve embodying the invention. Fig. 3 is a plan. Fig. 4 is a detail of the valve plunger.

The invention is exemplified in a refrigerating system comprising a compressor *a*, a condenser *b*, a refrigerant receiver *c*, a freezer *d* connected to the receiver by a pipe *c'* in which is included an expansion valve *c²*; a re-

turn pipe *e* leading from the freezer *d* to the suction side of the compressor *a*; and an automatic differential valve *f* included in the line between the freezer and the compressor.

The valve *f* comprises a body 10 provided with an inlet 11 to which the branch of the pipe *e* from the freezer is connected; an outlet 12 to which the branch of the pipe *e* which leads to the compressor is connected; a valve-seat 13 between the inlet and outlet; and a valve plunger 14 which is provided with a suitable liner 27 to engage the valve-seat 13 to close communication between the inlet 11 and the outlet 12 to prevent the flow of the refrigerant to the compressor. The plunger 14 is slidably guided in an upward extension 15 of the casing 10, and its upper end is attached to a diaphragm 16 by means of a head 17 which is screw-threaded to a stud 18 on the upper end of the valve plunger 14. The outer margin of the diaphragm is clamped by bolts 22 between a flange 20 integral with the extension 15 and a flange 21 of a housing 23. Bolts 22 also serve to secure the housing 23 to the top of the body 10 of the valve 10. Head 17 is vertically guided in a cylindrical portion 24 of the housing 23. The plunger comprises a lower wall in which the liner 27 is held, ribs 14^a which are slidable in the cylindrical guide 15 of the body 10, and a top wall 26, all of which are integrally formed. The liner may be removably secured to the plunger by screw 30. The diaphragm is exposed at all times to the pressure in the inlet side of the casing through ducts 25 formed in the margins of the wall 26 of the plunger.

A coil spring 31 engages the top of the head 17 to normally hold the valve closed and to resist its opening by the pressure of the refrigerant against the underside of the diaphragm 16. The lower end of said spring is confined by a lug 33 on the head 17, and an abutment member 34 engages the upper end of the spring and extends into it. Member 34 is arrested by a screw 35 which is threaded to a wall 36 integrally formed with the housing 23. By adjusting the screw 35, the pressure of the refrigerant required in the inlet side to open the valve may be varied to the desired predetermined point, so that the pressure of

the refrigerant in the freezer during the first period of operation will provide the desired temperature for such period.

A pin 40 extends and is slidable through screw 35 and has its lower end slidably mounted in abutment member 34. The upper end of the pin extends above the screw 35 so that the pin may be operated to control the operation of the freezer to produce differential predetermined pressure during the second period of the freezing operation. A device is provided whereby the pin 40 may be operated to compress the spring 31 to hold the valve closed until the desired predetermined greater pressure is attained in the inlet side of the valve-body. This device comprises a hand lever 41 which is pivoted at 42 in a bracket 43 which is integrally formed with the housing 23 and extends upwardly therefrom, a link 44 pivoted to the lever, and a plunger 45 which is slidably guided in a bridge 46 integrally formed with the bracket 43 and to which the link 44 is pivoted, and a screw 47 which is threaded to the plunger 45 and has its head adapted to engage the upper end of the pin 40. The lever is operable to shift the abutment screw 47 so that it will force the pin 40 downwardly to put the spring 31 under greater pressure and correspondingly increase its resistance to the opening of the diaphragm by the pressure of the refrigerant. Link 44, when the lever 41 is lowered into the position shown by dotted lines in Fig. 2, passes substantially into dead center relation between the lever fulcrum 42 and the pivot between the link and the plunger 45, so that the lever will be automatically held or locked in its lowered position to correspondingly lock the screw 47. By adjusting the screw 47, the stroke imparted to the pin 40 may be varied to vary the pressure required to shift the diaphragm to open the valve against the force of the spring 31.

The operation will be as follows: During the initial freezing period, the lever 41 will be raised so that screw 47 will be disengaged from the pin 40 so that the abutment member 34 will be free to engage the screw 35. At such time, the refrigerant passing through the jacket of the freezer *d* will be at a relatively low pressure, for example fifteen pounds, so that said substantial pressure will be maintained in the line between the receiver *c* and the controlling device *f*. At the end of the initial freezing period, when it is desired to carry on the freezing operation at a higher temperature, the operator will lower the lever 41 so that the screw 47 will engage pin 40 and force the member 34 downwardly to increase the resistance of spring 31 so that the valve 14 will not open until it retards the circulation of the refrigerant through the freezer by this predetermined higher pressure so that the latter period of the freezing

will be effected at this higher temperature to reduce the density of the product.

The invention exemplifies improved controlling mechanism for refrigerating systems, in which an automatic or pressure controlled valve is provided with means whereby it may be caused to open at predetermined differential pressures, so that by the simple manipulation of a lever, the operator may cause the freezing to be done at two different pressures or temperatures. The valve and the adjusting device are comprised in a single unit which may be readily installed in the suction line for the refrigerant. The invention also exemplifies a device of this character which is particularly adapted for controlling the operation of systems in which ammonia is used as the refrigerating agent.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a controlling device for refrigerating systems, the combination of a casing, a valve plunger in the casing, a diaphragm exposed to the pressure of fluid in the casing connected to operate the plunger, a spring applied to resist the movement of the diaphragm, an abutment screw for the spring, and a device for adjusting the spring independently of the screw so the diaphragm will be operable by different predetermined pressures.

2. In a controlling device for refrigerating systems, the combination of a casing, a valve plunger in the casing, a diaphragm exposed to the pressure of fluid in the casing connected to operate the plunger, a spring applied to resist the movement of the diaphragm, an abutment-screw for the spring, and a device for adjusting the spring independently of the screw so the diaphragm will be operable by different predetermined pressures comprising a lever.

3. In a controlling device for refrigerating systems, the combination of a casing, a valve plunger in the casing, a diaphragm exposed to the pressure of fluid in the casing connected to operate the plunger, a spring applied to resist the movement of the diaphragm, an abutment-screw for the spring, and a device for adjusting the spring independently of the screw so the diaphragm will be operable by different predetermined pressures comprising a lever and a pin extending through said screw.

4. In a controlling device for refrigerating systems, the combination of a casing, a valve plunger in the casing, a diaphragm exposed to the pressure of fluid in the casing connected to operate the plunger, a spring

applied to resist the movement of the diaphragm, an abutment-screw for the spring, and a device for adjusting the spring independently of the screw so the diaphragm will be operable by different predetermined pressures, comprising a lever, a slidable element operable by the lever, an adjustable abutment on said element, and a pin engaged by the adjustable abutment and extending through the screw.

5. In a device for controlling refrigerating systems, the combination of a casing, a valve plunger therein, means controlled by the pressure of the fluid in the casing for opening the valve, a spring for closing the valve, and a device for quickly adjusting the spring to permit the valve to be opened at two different predetermined pressures, comprising a lever and a self-locking connection 10 to hold the lever in one position.

6. In a refrigerating system, the combination of a refrigerant line, a valve in the suction side of the line between an evaporator and a compressor, a diaphragm for operating the valve, operable by the pressure of the refrigerant in said suction side of the refrigerant line to control the return of the refrigerant to the compressor, a spring applied to the diaphragm to force the valve into its 15 closed position, and means slidably mounted and shiftable readily from one predetermined position into another for adjusting the spring with respect to tension so as to control the opening of the valve by two predetermined differential pressures and cause the refrigerant to cool at two different predetermined temperatures.

Signed at Chicago, Illinois, this 1st day of February, 1927.
